(57) **CLAIM**

The ornamental design for a locking terminator and port cap, as shown and described.

DESCRIPTION

FIG. 1 is a front elevation view of my new design of the locking terminator and port cap of the present invention; FIG. 2 is a rear elevation view thereof;

FIG. 3 is a top plan view thereof, of which the bottom plan view is a mirror image; and,

FIG. 4 is a perspective view thereof.
